UNITED STATES PATENT OFFICE

WALTER L. KAUFFMAN, OF YOUNGSTOWN, OHIO

COMBINATION HANDLE AND STRAP HOLDER

Application filed July 18, 1930. Serial No. 468,967.

This invention relates to a combination handle and strap holder for suit cases and the like.

The principal object of this invention is to provide a device which is inexpensive of manufacture and reliable for the use to which it is put.

A further object of the invention is to provide a device of the class in which a handle is secured to the handle securing means comprising a metal member having an upwardly extending loop pressed upwardly from a central portion of a metallic member leaving an opening underneath said loop so that a strap may pass underneath said loop and over portions of the metallic member thereby making a secure hold of the handle regardless of its connection to a suit case or the like.

A still further object is to provide means for interlocking one end of the device which is secured to a ring attached to the handle, and riveting both ends of device to the suit case or the like.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

The invention is illustrated in the accompanying drawings, wherein:—

Figure 1 is a top plan view of the device with parts broken away.

Figure 2 is a cross section taken on line 2—2 of Fig. 1.

Figure 3 is a cross section taken on line 3—3 of Fig. 1.

Figure 4 is a side elevation of a suit case with my improved device attached thereto, and with the straps broken away in order to show more clearly how the same functions.

Figure 5 is a modification shown in perspective view of the device.

Figure 6 is a modification in section showing a portion of the metal part of the device either cast or welded.

Figure 7 is a top plan view of a metal strip before being formed.

By referring to the drawings it will be seen that I have provided a flat metal strip 1. This flat metal strip 1 is provided with a central loop 2 which is formed by the cutting of edges 3 and 4 and pressing upwardly forming the central loop 2. A loop 5 is formed at one end of said flat metal strip for the reception of a ring 6 to which is attached a handle 7. In order to form a reliable loop 5 a slot or slots 8 are formed in the flat metal strip 1 and tongues 9 are brought upwardly through this slot or slots 8 and folded back upon an upper edge 10 of the flat metal strip 1.

By referring to Fig. 1 it will be seen that rivet holes 11 and 12 are positioned so that the rivet hole 12 passes through one end of the flat metal strip 1, and through an upper portion of a suit case or the like 13. One rivet functions with the rivet hole 11 and passes through the flat metal strip 1 and through the upper portion of a suit case or the like 13. In order to carry out the material design of the suit case or the like 13 there is provided a cover portion 14 which may be of leather if the suit case or the like is made of leather. This cover portion is stitched to the suit case or the like 13 by means of a seam 15. By referring to Fig. 1 it will be seen that this cover portion 14 is made of one piece with a cut out lip portion 16 which functions underneath the central loop 2. One end of the cover portion 14 is reduced and passes around the loop 5 and is held by a rivet functioning in rivet hole 12.

By referring to Fig. 3 it will be readily seen that when straps 17 have been projected through a loop opening 18 which is formed between the central loop 2 and outside metal straps 19 the same are securely held not only in relation to the central loop 2 but also in relation to the handle 7 which is also a part of the metal strip 1.

By referring to Fig. 5 it will be seen that I have shown a modification of the device in that a metal loop 20 is formed from a metal strip 21. An end 22 has been cut free at a point 23 in order that a cover portion 14 may

be easily placed over this metal strip 21 by forming a slotted recess for the upturned outer end portion 24 of the metal loop 20. It will also be seen that the loop 5 in this modification is formed by a down and in-turned end and ends at a point 25 in order that a rivet functioning in a rivet hole 26 will pass through this down and in-turned end of a metal strip 21, and the end 22 of the metal loop 20.

By referring to Fig. 6 it will be seen that the flat metal strip 1 may be formed with a loop wherein the neck 27 is a solid piece of structure either made by casting or welding.

By referring to Fig. 7 it will be seen how the flat metal strip 1 is blanked out before being formed.

By referring to Fig. 4 it will be seen that the device is riveted to the suit case 13 by means of rivets 28 and 29, these rivets functioning in the rivet holes 11 and 12 respectively. These rivets also pass through an upper portion of the suit case 13.

It will be clear that in the event that the rivets 28 and 29 should pull through the upper portion of the suit case 13 the handle 7 will still be firmly attached, due to the straps 17 passing through the loop openings 18, formed between the central loop 2 and the outer straps 19 of the flat metal strip 1.

What I claim is:—

1. In a combination handle and strap holder a single metal strip, a central loop pressed upwardly and formed from a central portion of said single metal strip, a ring securing means formed at an inner end of said single metal strip, a ring connecting said ring securing means with one end of the handle, rivets securing said single metal strip at both ends to a suit case or the like, the strap passing over said single metal strip and under said central loop, substantially as described.

2. In a combination handle and strap holder comprising a single metal strip, a central loop pressed upwardly and formed from a central portion of said single metal strip, a loop formed at one end of said single metal strip for the purpose of holding a ring to which is attached the handle, the strap passing under the central loop formed from the single metal strip and over the metal strip, means for securing said single metal strip at both ends to a suit case or the like, substantially as described.

3. In a device of the class described comprising a suit case or the like, in combination with a pair of metal strips, a central loop pressed upwardly and formed from a central portion on each of said metal strips, one end of each metal strip provided with slots, a loop formed at one end of each of said metal strips by turning an end downwardly and then upwardly through said slots and then falling back upon the upper portion of said metal strips, a ring connected to each

of said loops, a handle secured to said rings, straps passing between the central loop portion and the metal strip, means for securing each of said metal strips at both ends to a case or the like, substantially as described.

4. In a device of the class described comprising a suit case or the like, a pair of metal strips, a central loop pressed upwardly and formed from a central portion of each of said metal strips, a loop formed at one end of each of said metal strips, a ring connected to each of said loops, a handle secured to said ring, straps passing over said metal strips and under the central loop formed on each of said metal strips, rivets securing said metal strips to a suit case or the like, substantially as described.

In testimony whereof I affix my signature.

WALTER L. KAUFFMAN.
